UNITED STATES PATENT OFFICE.

SAMUEL F. KLOHS, OF CHICAGO, ILLINOIS.

CAR-COUPING.

1,142,104.

Specification of Letters Patent. Patented June 8, 1915.

Application filed January 27, 1915. Serial No. 4,660.

To all whom it may concern:

Be it known that I, SAMUEL F. KLOHS, a citizen of the United States, residing at Chicago, in the county of Cook and State of Illinois, have invented certain new and useful Improvements in Car-Couplers; and I do hereby declare the following to be a full, clear, and exact description of the invention, such as will enable others skilled in the art 10 to which it appertains to make and use the same.

This invention relates to car couplers of the vertical plane type and its principal object is to provide means whereby the space 15 within the contour lines of the coupler between the head and knuckle may be effectively increased when the coupler is in use, to thereby afford a greater clearance for the knuckle of the adjacent coupler than now 20 exists in couplers having standard Master Car Builders' contour lines.

Further important objects of my invention are to so construct the coupler that it may be coupled without difficulty with a coupler 25 having standard contour lines; and to provide means for effecting an inward rotation of the outer end of the knuckle while the latter is maintained in coupled relation, thereby not only compensating for wear at the 30 outer end of knuckles, but also operating to make the coupled knuckles cling close together and effectually maintain their engagement when subjected to pulling strains, as will later appear herein.

Owing to the comparatively small clearance allowed between the engaging parts of interlocked couplers having contour lines conforming to the present Master Car Builders' standard, the couplers upon adjacent 40 cars are liable to bind upon each other when the cars are moving backwardly over uneven or vertically curved track that causes the abutting ends of the cars to move vertically in opposite directions. Such a binding of 45 the couplers causes the end of one car to carry the weight of the end of the opposite car, and this frequently results in the breaking of carrier irons and the rupture of the connections of the coupler with its car. By 50 my construction any such binding of the couplers is relieved and prevented by permitting the knuckles to yield as occasion requires, thus increasing the clearances, the means employed to effect this purpose being 55 also effective to prevent severe strains from being imparted to the knuckle and to the

lugs of the head to which the knuckle is connected when the train is being started or is being drawn along.

Figure 1 is a horizontal sectional view of 60 a car coupler constructed in accordance with my invention. Fig. 2 is a view similar to Fig. 1, showing the positions of the parts when subjected to a pulling strain and also showing, in dotted lines, the position of the 65 coupler connected thereto. Fig. 3 is a view of the coupler showing the knuckle open, the view being partly in horizontal section. Fig. 4 is a vertical sectional view showing the knuckle closed. Fig. 5 is a front view of 70 the coupler showing the parts in coupled position, the knuckle and a portion of the coupler head being in transverse section. Fig. 6 is a front view of the coupler showing the parts in lock-set position, the knuckle 75 and part of the coupler head being in transverse section. Fig. 7 is a front view of the coupler showing the knuckle thrown open by the knuckle opening lever, the knuckle and a portion of the coupler head being in transverse section. Fig. 8 is an enlarged view of 80 the knuckle lock and its lifting devices, the lock and the upper lifting member being in vertical section. Fig. 9 is a horizontal section on the line 9—9 of Fig. 8. Fig. 10 85 is a plan view of a slide for connecting the tail of the knuckle to a spring. Fig. 11 is a front elevation of the part shown in Fig. 10. Fig. 12 is a perspective view of the knuckle lock. Fig. 13 is a view showing two couplers 90 of standard contour coupled together, the nature of the wear on the knuckles being shown in dotted lines at a, a. Fig. 14 is a horizontal section of a modified form of the invention. Fig. 15 is a horizontal section 95 of the coupler shown in Fig. 14, the knuckle being in its forward position.

The knuckle 1 is pivoted to the coupler head 2, so as to be capable not only of a rotary movement but also of a sliding movement inwardly and outwardly with respect to the head. In order to permit this the knuckle and head preferably have a pin and slot connection, the slot 3 being preferably formed in the knuckle and the pin 4, which 100 extends through said slot, being carried by the coupler head.

The tail of the knuckle is preferably formed with a hooked portion 5 as such a construction operates to prevent the knuckle 110 from being disconnected from the coupler head should the pin 4 break, and also affords

a means for permitting the spring devices to retain control of the knuckle in all positions of the latter. The side wall of the coupler head is provided with an elongated 5 aperture 6 to receive the hooked portion 5 of the knuckle and permit the same to move back and forth therein as the knuckle executes its sliding movements outwardly and inwardly to increase or diminish the clearance 10 or space between the forward end of the knuckle and the coupler head while these parts are in coupled relation. The under side of the tail of the knuckle is preferably provided with a downwardly extending 15 flange 7 of a length permitting it to constantly coöperate with an upwardly extending lug 8 on the forward part of the yielding slide 9, the control of the spring devices over the knuckle being thereby always assured.

20 As shown in dotted lines in Figs. 1 and 2, the forward face of the lug 7 is preferably flattened and the adjacent inner face of the lug 8 upon the slide is curved, so that these parts may rock easily on each other as the outer 25 end of the knuckle rotates inwardly or outwardly during the sliding movements executed by the knuckle while in coupled relation. The pivot lugs 10 of the coupler head are preferably made large enough to cover 30 the slot 3 on the knuckle in all positions of the latter.

The lock 11 for maintaining the knuckle in coupled relation is preferably mounted on the slide 9 so as to partake of the movements 35 of the latter and is preferably vertically slideable so as to gravitate to locked position. Its forward face 12 next to the knuckle 1 may be beveled or inclined so as to provide a firm and extended bearing face for the 40 knuckle when the same is drawn forward and rotated while in coupled relation, as shown in Fig. 2. The bottom of the lock is recessed at 13 to permit the knuckle to swing in and out when the lock is raised sufficiently, and to form a shoulder 14 that is 45 adapted to be acted upon by the upper side of the hooked portion of the knuckle 1. The shoulder 14, as shown, is preferably sloping or inclined so as to be engaged by the tail 50 of the knuckle and thereby cause the lock 11 to be raised when the knuckle swings open, thus releasing the lock from its lock-set supporting device.

The lock 11 may be raised either from the 55 top or from the bottom of the coupler. When the lock is lifted from the top of the coupler, the lifting member 15, which slides vertically in the head 2 and which is flexibly connected to the lock so as to permit the latter to move with the slide 9, is preferably formed with an eye 16 suitable for the attachment of an uncoupling chain or lever. To flexibly connect the lock 11 and lifting member 15, a link 17 may be used. 60 65 This link, which is preferably housed within

the lock 11 and lifting member 15, is formed with a hook 18 at its lower end and with an eye 19 at its upper end. The opening in the lock and that in the lifting member into which the link 17 extends are made sufficiently large to enable the lock 11 to move with the slide 9 without affecting the member 15. The lock 11 is engaged by the hook 18, while a pin 20, which passes through the eye 19, connects the link 17 to the lifting member 15. 70 75

The lifting member 15 is preferably so constructed that it coöperates with a lever 21 not only to rotate the knuckle 1 outwardly, but also to hold the lock 11 in an elevated or lock-set position while the knuckle occupies its coupled position. To effect these purposes the lower end of the lifting member 15 is preferably provided with a projection 22 and with a recess 23 above said projection. As seen from Fig. 7, when the projection 22 comes into engagement with the short arm of the lever 21, which is pivoted on the head 2 by means of a pin 24, the longer arm of said lever presses 80 against the knuckle tail and forces the knuckle 1 to turn outwardly around its pivot pin 4. As seen in Fig. 6 the end of the short arm of the lever 21 is adapted to enter the recess 23 and maintain the lock in an elevated position, the eye or slot 25 in the lever through which the pivot pin 24 passes being elongated so that the said lever can gravitate into the lock sustaining position described. The lower end of the lever 21 90 preferably bears against a shoulder 26 on the upper face of the knuckle tail; this permits the knuckle to execute its sliding movements in a longitudinal direction without any possibility of injuring the knuckle- 95 throwing lever. 100 105

The side of the slide 9 nearer the guard arm of the coupler is provided with one or more inclined faces 27 and 28, and the interior of the head is likewise provided with coöperating inclined surfaces 29 and 30. The opposite edge 31 of the slide is also preferably inclined so as to be parallel with the inclined faces 27 and 29, said edge 31 being adapted to slide upon a similarly inclined rib or shoulder 32 on the inside of the coupler head. It results from this construction that the slide 9 and lock 11 mounted thereon move laterally when the knuckle 1 slides outwardly while in coupled relation, thus causing the outer end of the knuckle to swing or rotate inwardly toward the coupler head and thereby prevent the escape of the knuckle on the opposite coupler when the space therefor between the knuckle 1 and head 2 is increased by the yielding forward movement of the said knuckle 1. 110 115 120 125

The spring 33 which is housed within the coupler, is preferably connected to the slide 9 by a bolt 34 which passes through the 130

spring and through an opening 35 in the slide. The head of the bolt 34 bears against the front of the slide 9 and the hole 35 is made large enough to prevent binding on 5 the bolt when the slide moves. The forward end of the spring 33 bears against a plate or follower 36 which itself bears against shoulders or stops 37 and 38 on the interior of the coupler. The rear end of 10 the spring bears against a follower 39 which is maintained on the bolt 34 by means of a nut 40 on the end of said bolt.

The modification of my invention shown 15 in Figs. 14, and 15, illustrates the use of a vertically sliding lock 41 which remains stationary during the sliding, turning movements of the slotted knuckle 42 while the latter is in coupled relation. The side 43 of the knuckle facing the lock, as shown, is 20 preferably curved and the adjacent portion of the face 44 of the lock is similarly curved so as to maintain a substantial bearing between the knuckle and the lock in all coupled positions of the knuckle. The face 44 25 of the lock 41 stands at an angle to the longitudinal axis of the coupler and therefore as the knuckle 42 moves outwardly it is caused to turn slightly on the pivot pin 45, the outer end of the knuckle moving inwardly so as to insure the maintenance of 30 its coupling engagement with the knuckle of the opposite coupler. The means heretofore described for yieldingly resisting the movements of the knuckle and for opening 35 the same are equally applicable to this form of my invention and are preferably employed.

What I claim is:

1. The combination with a coupler having 40 a pivoted knuckle which is adapted to move longitudinally with respect to the head thereof while the parts are in coupled relation, a lock for said knuckle, and spring means operatively connected to said knuckle 45 for retracting the same, said means being arranged within the contour of the coupler and lying wholly within a line which extends parallel to the longitudinal axis of the coupler and which passes through the pivotal axis on which the knuckle turns when 50 rotating outwardly.

2. In a car coupler, the combination with a coupler head, of a knuckle yieldingly mounted thereon, said head and knuckle having a pin and slot connection permitting the knuckle to move relatively to the coupler head in the line of draft while the knuckle is locked, a lock for maintaining the knuckle in coupled relation with respect 55 to said head, and a spring device operatively connected to the tail of said knuckle and pulling thereon in all positions of the latter whether the knuckle is open or closed.

3. In a car coupler, the combination with 60 a coupler head, of a knuckle movably

mounted thereon so as to permit its outer end to approach and recede from the coupler head while the parts are in coupled relation, and means for causing the outer end of said knuckle to rotate inwardly when it 70 is drawn outwardly.

4. In a car coupler, the combination with a coupler head, of a knuckle movably mounted thereon so as to permit its outer end to approach and recede from the coupler head while the parts are in coupled relation, and means for maintaining the knuckle in coupled relation with said head, said means being operative to cause a turning movement of said knuckle while the latter is in coupled relation with said head. 75

5. In a car coupler, the combination with a coupler head, of a knuckle movably mounted thereon so as to permit its outer end to approach and recede from the coupler head while the parts are in coupled relation, means for yieldingly connecting said head and knuckle, and means for causing an inward turning movement of the outer end of said knuckle while the latter is in coupled relation with said head. 80

6. In a car coupler, the combination with a coupler head, of a knuckle which is mounted on said head so as to be capable of movement with respect thereto while the 95 parts are in coupled relation, and a lock for maintaining said knuckle in coupled relation, said lock being movable with said knuckle.

7. In a car coupler, the combination with 100 a coupler head, of a knuckle which is mounted on said head so as to be capable of movement with respect thereto while the parts are in coupled relation, and a lock for maintaining said knuckle in coupled relation, said lock being mounted on said head 105 so as to be movable forwardly and laterally with respect thereto while maintaining said knuckle and head in coupled relation.

8. In a car coupler, the combination with 110 a coupler having a head and rearwardly extending chambered stem, of a knuckle movably mounted thereon so as to permit its outer end to approach and recede from the coupler head while the parts are in coupled 115 relation, a lock for said knuckle, and spring means arranged within the stem for retracting said knuckle when the latter is not subjected to draft force, said means being operatively connected to the tail of said 120 knuckle in all positions of the latter whether the knuckle is open or closed.

9. In a car coupler, the combination with a coupler head, of a knuckle yieldingly mounted thereon, a spring, means for operatively connecting said spring and knuckle, and a lock for maintaining said knuckle in coupled relation, said lock being movable by said connecting means. 125

10. In a car coupler, the combination with 130

a coupler head, of a knuckle having a pin and slot connection therewith, a spring, means for operatively connecting said spring and knuckle, a lock for said knuckle 5 mounted upon said connecting means, and means for moving the tail of said knuckle toward the knuckle side of said head when the coupler is subjected to draft forces.

11. In a car coupler, the combination with 10 a coupler head, of a knuckle movably mounted thereon so as to permit its outer end to approach and recede from the coupler head while the parts are in coupled relation, a spring, devices for operatively connecting 15 said spring and knuckle, and a lock for maintaining said knuckle in coupled relation, said head and said devices for operatively connecting said spring and knuckle being relatively movable and being formed 20 with engaging inclined faces.

12. In a car coupler, the combination with 25 a coupler head, of a knuckle movably mounted thereon, and a lock for maintaining said knuckle in coupled relation with respect to said head, said lock being movable toward the knuckle side of said head while engaging the knuckle to restrain it from moving outwardly to open position when subjected to a pulling force.

13. In a car coupler, the combination with 30 a coupler head, of a knuckle movably mounted thereon so as to permit its outer end to approach and recede from the said head while the parts are in coupled relation, a lock movable coextensively with said knuckle for retaining the latter in coupled relation, spring means for moving the said knuckle and lock to retracted position, means mounted on said coupler and engaging 35 the rear side of the tail of the knuckle for moving the knuckle to open position 40

when released from said lock, and means connected to said lock for actuating said knuckle opening means, said knuckle opening means being mounted in said coupler 45 head in a position to be engaged by said actuating means and to engage the rear side of the knuckle tail when said knuckle and lock are in retracted position.

14. In a car coupler, the combination with 50 a coupler head, of a knuckle movably mounted thereon so that its outer end may approach and recede from the said head when the parts are in coupled relation, a vertically movable lock for maintaining the knuckle 55 in coupled relation, and means for lifting said lock, said lock being movable coextensively with the knuckle when the latter moves while in locked position.

15. In a car coupler, the combination with 60 a coupler head, of a knuckle movably mounted thereon so that its outer end may approach and recede from said head when the parts are in coupled relation, and a lock for maintaining said knuckle in coupled relation, said lock being adapted to engage the 65 tail of said knuckle to effect an inward rotation of the outer end of said knuckle when the knuckle is drawn outwardly.

16. In a car coupler, the combination with 70 a coupler head, of a knuckle movably mounted thereon, and means whereby the outer end of said knuckle is caused to swing inwardly when said knuckle is subjected to a pulling force.

In testimony whereof I affix my signature in the presence of two subscribing witnesses.

SAMUEL F. KLOHS.
